UNITED STATES PATENT OFFICE.

EDWARD C. WENTE, OF NEW HAVEN, CONNECTICUT, ASSIGNOR TO WESTERN ELECTRIC COMPANY, INCORPORATED, OF NEW YORK, N. Y., A CORPORATION OF NEW YORK.

TELEPHONE-TRANSMITTER.

1,333,744.

Specification of Letters Patent. Patented Mar. 16, 1920.

Application filed December 20, 1916. Serial No. 137,978.

To all whom it may concern:

Be it known that I, EDWARD C. WENTE, a citizen of the United States, residing at 162 York St., New Haven, in the county of New Haven and State of Connecticut, have invented certain new and useful Improvements in Telephone-Transmitters, of which the following is a full, clear, concise, and exact description.

10 This invention has reference to improvements in telephone transmitters for the reproduction, recording, analyzing and measuring of sound waves.

More particularly it relates to telephone transmitters of the condenser type, its object being to produce a transmitter that gives practically a uniform transmission over a far greater range of frequency than has heretofore been obtained.

20 It has been found that diaphragms, such as are used in telephones, phonographs and other acoustic apparatus, have a more or less marked natural period for one or more frequencies and if acted upon by impulses 25 of these frequencies will respond much more than for materially different periodicities. The natural period depends in general on the mass and the elasticity of the diaphragm, decreasing with increase of mass, 30 and increasing with increase of elasticity.

In the usual telephone diaphragm, the lowest natural period is in the neighborhood of 1000 cycles per second which is well within the range of those frequencies used 35 in speech. Because of this natural periodicity and the resulting inequality of response to impulses of different frequencies, a telephone diaphragm will distort the speech waves which are impressed on it when the 40 resonance point falls within that range which is of importance in speech. If, however, the elasticity of the transmitter is increased sufficiently, this resonance point will be removed outside the speech range and

45 there will be practically equal response to all impressed frequencies of the same intensity and consequently there will be little or no distortion of the impulses impressed on the diaphragm. This maximum 50 response at the resonance point can also be considerably decreased in value by increasing the damping factor of the vibrating system. The damping factor in general de-

pends only upon the frictional forces and upon the inertia, being proportional to the 55 frictional forces, and inversely proportional to the inertia or mass of the moving system. Increasing the damping factor gives the 60 vibrating system a frequency characteristic of response more nearly of the ideal form which would be represented by a line parallel to the axis of frequency, indicating thereby an equal response to all frequencies.

This invention has for its purpose primarily to make improvements in the quality 65 of speech as transmitted by previous telephonic or phonographic apparatus and accomplishes this purpose by increasing the elasticity and the damping factor of the 70 vibrating system.

70 For the accomplishment of the objects above set forth, this invention embodies a transmitter of sound waves consisting of a sheet of stretched material and a stationary member in close face to face relation with 75 each other. The close adjustment of the two members to each other greatly increases the elasticity of the diaphragm and its damping coefficient in a manner hereinafter described, so that the natural period peak is 80 removed beyond the upper limit of the frequency range of importance to speech and is reduced to a minimum.

80 For the better understanding of this invention, it is described in connection with 85 a condenser transmitter although the scope of the invention is not limited thereto, but it may be applied to any type of a vibration instrument without departing in any wise from the spirit of this invention.

90 The novel features of this invention are particularly pointed out in the appended claims, for a better understanding of which reference is made to the following description, taken in connection with the accompanying drawings.

95 Figure 1 shows the relation between the amplitude of forced oscillations transmitted by a stretched diaphragm and the frequency of the impressed sound waves.

100 Fig. 2 gives a corresponding curve for a stretched diaphragm used as one plate in a condenser transmitter and in intimate relation to the other plate in accordance with this invention.

105 Fig. 3 illustrates a cross sectional view of

a condenser transmitter illustrating one embodiment of this invention.

Fig. 4 represents an application of this invention to the reproduction or recording of sound waves.

The resonance curve of a stretched diaphragm is somewhat similar in form to that shown in Fig. 1, in which F represents the frequency of the impulses incident upon the 10 diaphragm, and I represents the degree of response of the diaphragm to the incident frequencies. Such a diaphragm has a natural period of vibration and transmits vibrations in the neighborhood of that period 15 with far greater intensity than other vibrations. An unstretched telephone diaphragm may have a natural frequency in the neighborhood of one thousand cycles per second but by suitable stretching this natural frequency can be raised to the neighborhood of 20 4000 cycles as shown in the figure. Such a diaphragm would be undesirable for the analysis or accurate reproduction of sound waves because of the great emphasis with 25 which vibrations of a certain pitch would be brought out to the detriment of the other incident frequencies, thereby producing distortion. In this description we shall consider that the upper limit of the frequency 30 range of importance to speech is approximately 8000 cycles per second.

Fig. 2 gives the resonance curve for the vibrating system embodied in this invention in which the resonance peak is outside the 35 frequency range important to speech, being in the neighborhood of $F=16000$ cycles. Hence there will be practically a uniform responsiveness for the whole speech range. The change from Fig. 1 to Fig. 2 is brought 40 about by increasing to a high degree the elasticity and the damping factor of the vibrating system according to the means embodied in this invention and described in connection with a condenser transmitter.

45 In the condenser transmitter illustrated in Fig. 3 of the drawing, the diaphragm 6 and the plate 7 constitute the two plates of the condenser part of the transmitter. Sound waves, incident on the diaphragm, cause it 50 to vibrate, thereby causing variations in the effective thickness of the dielectric between the plates and consequently giving rise to variations in the capacity of the condenser. The diaphragm 6 is shown clamped near its 55 outer edge by means of the clamping rings 8 and 9. Ring 11 has, in contact with the diaphragm, a projection 12 that serves to stretch the diaphragm when suitable compression is exerted between the clamping rings 8 and 9 60 and the ring 11 by means of the bolt 13. The back electrode or plate 7 is fastened to an insulating disk 14 of suitable insulation material such as amber or glass. This disk rests in a recess 15 of the bushing 16 in such 65 a manner that, when the rim of the bushing

is in contact with the diaphragm near its outer edge, the plate is separated from the diaphragm by a very thin film of air having a thickness of the order of 0.0005 of an inch. In order to have uniform air space of such 70 dimensions, it is necessary to have the plate and the rim of the bushing very accurately machined and polished. For a final adjustment of the gap, it may be found desirable to insert a thin washer of mica 10, or other 75 suitable material, in the recess 15, in which the insulating disk rests. The diaphragm may be stretched by any of the suitable methods known in the art. 17 is a locking ring for the insulating disk and the bushing; 18 is a locking ring for the bushing and 80 the stretched ring.

Such an arrangement brings into play the high elastic and frictional forces that are necessary to increase the frequency value at 85 which the natural period occurs. When the diaphragm moves in toward the plate, for example, two types of motion take place in the thin film of air between the diaphragm 6 and the plate 7, namely, a lateral escape 90 toward the periphery of the plate and a compression. On account of the extremely narrow passage way between the two electrodes, a large frictional force comes into play so that the lateral motion of the air is 95 greatly impeded. Being unable to escape, the air undergoes a compression, thereby giving additional stiffness to the system, which is equivalent to increasing the effective elasticity. For example, a diaphragm 100 of sheet steel 1.5 inches in diameter, stretched to the elastic limit, may be made to have a natural frequency of about 4000 and, when the vibrations are in air, a damping coefficient of about 1000. If the same stretched 105 diaphragm is placed in a condenser transmitter with a plate adjusted to within 0.0005 of an inch from the diaphragm, the natural frequency is raised to about 16000 and the damping coefficient to about 6000. 110 The increase in natural frequency displaces the resonance point to a region far beyond that heretofore attained and the enormous increase in the damping coefficient very materially flattens the characteristic of response. 115

Fig. 4 shows how this invention may be adapted to be used as an instrument for reproducing, recording or measuring sound waves. 20 is a condenser transmitter of the 120 type herein described. Connected to one terminal of the condenser is the heated filament 21 of a thermionic amplifier 22. To the other terminal of the condenser is connected the grid element 23 of the amplifier, 125 this amplifier being the usual thermionic amplifier of the audion type now well-known in the art. Its output circuit contains the primary transformer winding 25. The secondary winding 26 may be included 130

in a suitable receiving circuit for the amplified electric oscillations from the amplifier which are proportional in intensity and magnitude to the signal waves impressed on the transmitter. 28 is a battery or other direct source of current of electromotive force which is used for polarizing the condenser. In series with source 28 is a high resistance 29 which prevents a change of charge on the condenser plates when the diaphragm is vibrating. The input circuit has a source of voltage 30. With such an arrangement, sound waves incident upon the condenser transmitter 20 would produce corresponding electric oscillations in the input circuit of the amplifier 22, which would appear in amplified form in its output circuit 32, where they would be either passed on to another amplifier for further amplification, or connected to a system containing a suitable receiving or recording device.

The arrangement of the circuit just described does not form a part of this invention but is described and claimed in a co-pending application of Hartley, Serial No. 53,429, filed September 30, 1915. This invention relates solely to the device shown in Fig. 3. Although this device is shown and described as a telephone transmitter it is to be understood that it may serve equally well as a receiver, and although it has been shown as a condenser transmitter or receiver, it may be used equally well with an electromagnetic receiver or transmitter or a microphonic transmitter by such obvious changes as will occur to any one skilled in the art. In other words the invention consists broadly in adjusting a diaphragm which is to vibrate in accordance with speech waves, so close to an adjacent face that the inclosed body of air will act to very largely increase the effective elasticity and damping coefficient of the vibrating diaphragm.

45 What is claimed is:

1. A telephone device comprising a vibrating member the normal natural frequency of which is within the range of speech frequencies, and means for increasing the natural frequency of said vibrating member above the range of essential speech frequencies.

50 2. A device for the transmission of sound composed of two members, said members being in face to face relation but having their major portions out of contact with each other and yet so close together as to provide a means for greatly increasing the elasticity of the system.

60 3. A device for the transmission of sound provided with two electrodes, one of said electrodes constituting a vibrating member having a natural period of vibration, said electrodes being in face to face relation and situated so close together that the lowest

natural frequency of vibration of said device is beyond the frequency range of importance in speech.

4. A telephone transmitter composed of two members, said members being in face to face relation with each other, one of said members constituting a vibrating element having natural frequencies of vibration, the other of said members consisting of a plate separated from said vibrating member by a thin film of a fluid dielectric, said film being a means for causing the lowest natural frequency of said vibrating member to occur at a frequency beyond the speech range.

5. In a telephone transmitter, the combination of two electrodes, said electrodes having the areas of their facing portions sufficiently extensive to establish an appreciable electrostatic relation between them, one of said electrodes being a sheet of stretched material, said electrodes being in a close face to face relation, thereby greatly increasing the elasticity of said sheet.

6. In a telephone transmitter, the combination of two electrodes, said electrodes having the areas of their facing portions sufficiently extensive so as to establish an appreciable electrostatic relation between them, one of said electrodes being a stretched diaphragm, the other being a plate in close proximity to said diaphragm, the two electrodes being so close to each other that the damping of said diaphragm is thereby greatly increased and that the lowest natural vibration frequency of said diaphragm occurs at a frequency beyond the speech range.

7. A device for the transmission of sound comprising two members, one of said members being a diaphragm, said members being in such close face to face relation that the movement of the inclosed film of air laterally is appreciably retarded by friction, whereby the elasticity of the diaphragm is greatly increased.

8. A device for the transmission of sound comprising two members, one of said members being a diaphragm, said members being in close face to face relation with each other, and means comprising a film of air of less than 25 ten thousandths of an inch in thickness, whereby the elasticity of the diaphragm is greatly increased.

9. A telephone transmitter comprising two members in close face to face relation and having their major portions out of contact with each other a distance less than 25 ten thousandths of an inch.

10. A telephone transmitter comprising two members in close face to face relation, one of said members being a diaphragm, said members having their major portions out of contact with each other a distance less than 25 ten thousandths of an inch.

11. A telephone transmitter comprising a diaphragm and a plate in close face to face

relation and having their major portions out of contact with each other a distance less than 25 ten thousandths of an inch.

12. A telephone transmitter comprising two members in close face to face relation with each other, one of said members being a stretched diaphragm, said members having their major portions out of contact with each other a distance less than 25 ten thousandths of an inch.

13. A telephone transmitter comprising a stretched diaphragm and a rigid plate in close face to face relation with each other, and having their major portions out of contact with each other a distance less than 25 ¹⁵ ten thousandths of an inch.

In witness whereof, I hereunto subscribe my name this fifteenth day of December, A. D., 1916.

EDWARD C. WENTE.
